[57] CLAIM

The ornamental design for a handle, as shown and described.

DESCRIPTION

FIG. 1 is a perspective view of a handle showing our new design, the suitcase being shown in broken lines for illustrative purposes only;

FIG. 2 is an enlarged, left side elevational view thereof;

FIG. 3 is an enlarged, front elevational view thereof;

FIG. 4 is an enlarged top perspective view of the gripping portion shown separately for ease of illustration;

FIG. 5 is a side elevational view taken from the rear of FIG. 4;

FIG. 6 is a bottom plan view of FIG. 4;

FIG. 7 is a sectional view taken in the direction of the arrows on line 7—7 of FIG. 6.

The rear of the handle is unornamented.
